[57] **CLAIM**

The ornamental design for a combined integrated voice data terminal and standalone keyboard, as shown and described.

DESCRIPTION

FIG. 1 is a top front and right side perspective view of a combined integrated voice data terminal and standalone keyboard showing our new design;

FIG. 2 is a top plan view thereof on a reduced scale showing a portion of the phone cord removed for ease of illustration;

FIG. 3 is a left side elevational view thereof on a reduced scale;

FIG. 4 is a right side elevational view thereof on a reduced scale;

FIG. 5 is a rear elevational view thereof on a reduced scale; and

FIG. 6 is a top front right side perspective view thereof showing the keyboard removed and replaced in an operative position.
